UNITED STATES PATENT OFFICE

168,602

CORNER TABLE

Everett A. Swanson, Naval Base, S. C.

Application December 10, 1951, Serial No. 17,675

Term of patent 3½ years

(Cl. D33—3)

To all whom it may concern:

Be it known that I, Everett A. Swanson, a citizen of the United States, residing at Naval Base, in the county of Charleston and State of South Carolina, have invented a new, original, and ornamental Design for a Corner Table, of which the following is a specification, reference being had to the accompanying drawing, forming a part thereof.

In the drawing:

Fig. 1 is a front perspective view of a corner table showing my new design.

Fig. 2 is a rear perspective view thereof.

I claim:

The ornamental design for a corner table, substantially as shown.

EVERETT A. SWANSON.
